(57) **CLAIM**

I claim the ornamental design for a front cover for lock, as shown and described.

DESCRIPTION

FIG. 1 is a front perspective view of a front cover for lock;

FIG. 2 is a back perspective view of FIG. 1;

FIG. 3 is a front elevational view of FIG. 1;

FIG. 4 is a back elevational view of FIG. 1;

FIG. 5 is a left side elevational view of FIG. 1;

FIG. 6 is a right side elevational view of FIG. 1;

FIG. 7 is a bottom view of FIG. 1; and,

FIG. 8 is a top view of FIG. 1.

The broken line showing in the drawing is included for the purpose of illustrating portions of the article that are not part of the claimed design lines in the drawings depict portions of the front cover for lock that forms no part of the claimed design.

1 Claim, 5 Drawing Sheets
